BATCHMETER

Rudolph F. Lindow, Milwaukee, Wis., assignor to
 Chain Belt Company, Milwaukee, Wis., a corporation of Wisconsin

Application October 26, 1931, Serial No. 571,265

16 Claims. (Cl. 161—1)

This invention relates to mechanism for timing the operations of various types of machines, such for example as concrete mixers, such mechanism being commonly known as a batchmeter, 5 and has for one of its objects to improve prior constructions of this type whereby a more efficient batchmeter will result.

A further object of the invention is to provide a device of this character which is susceptible of 10 infinitely fine adjustment whereby the length of the timing operation may be very accurately controlled.

A further object of the invention is to provide 15 a batchmeter which includes a driven member which always travels a fixed predetermined distance during each timing cycle regardless of the length of that cycle and in which variations in the length of the timing cycle are accomplished by varying the rate of travel of said driven member throughout said predetermined distance.

A further object of the invention is to provide 20 a batchmeter having a driven timing member which always occupies the same relative position at the beginning and close of the timing cycle whereby it may always be in position to begin a new timing cycle without the necessity for resetting or returning the apparatus to a fixed or variable starting point.

A still further object of the invention is to 25 provide a batchmeter in which the force for driving the driven member is applied by a yielding means such for example as a tension spring, the tension of which is automatically relieved at the end of a timing cycle in order to stop the drive.

A still further object of the invention is to improve and simplify the signal-operating mechanism of the batchmeter whereby a signal may be given at the beginning of the timing operation, at the close thereof, and a warning signal 30 may also be given at a predetermined period prior to the close of the timing cycle.

With the above and other objects in view which will appear as the description proceeds, the invention consists in the novel details of construction and combinations of parts more fully hereinafter described and particularly pointed out in the appended claims.

Referring to the accompanying drawings forming a part of this specification in which like reference characters designate like parts in all the views:—

Figure 1 is a front elevational view of a batchmeter constructed in accordance with the present invention, the cover or face plate of the housing being removed to expose the operating parts,

and the parts being shown in the positions they occupy in their state of rest at the close of and prior to the beginning of a timing operation;

Figure 2 is a transverse sectional view taken approximately on the plane indicated by the line 2—2 of Figure 1, looking in the direction of the arrows;

Figure 3 is a view similar to Figure 1 showing the parts in the positions they assume immediately after the starting of a timing operation; 10

Figure 4 is a transverse sectional view taken approximately on the plane indicated by the line 4—4 of Figure 3;

Figure 5 is a sectional elevational view looking from the rear of the mechanism and taken approximately on the plane indicated by the line 5—5 of Figure 6, the parts being shown in the positions they occupy just preceding the close of the timing operation and at the point when the intermediate or warning signal is about to be 20 given;

Figure 6 is a transverse sectional view of the parts shown in Figure 5, taken approximately on the plane indicated by the line 6—6 of Figure 5, looking in the direction of the arrows; and 25

Figure 7 is a diagrammatic elevational view of a portion of a concrete mixer illustrating the relative position of the batchmeter, the driving means therefor, and one means of starting the batchmeter to begin a timing operation, through 30 the movement of the arm which carries the charging skip of the mixer.

Referring more particularly to Figures 1 to 6 inclusive of the drawings the timing mechanism comprises a casing or housing 10 in which is 35 journaled in a suitable bearing 11 the power or driving shaft 12. The inner end of said shaft 12 carries the driving cam or eccentric 13, fast thereto, the periphery of which cam is engaged by a roller 14 carried by the inverted T-shaped 40 operating lever 15 which is journaled on a shaft 16 carried by bearing ears or lugs 17 rigid with the casing 10. A coil spring 18 has one end anchored to an extension 15' of the operating lever 15 and its other end secured to a suitable 45 eye 19 carried by the casing 10, and maintains the roller 14 in engagement with the driving cam or eccentric 13, as will be readily understood.

One arm of the T-shaped lever 15 is recessed to receive a hardened steel ball 20 which is 50 adapted to engage the surface 21 of an arm 22 which is rigid with housing 23 of an intermittent gripping device, here shown as comprising a one-way clutch of the roller type.

As best shown in Figures 3 and 6 the said 55

clutch, in addition to the housing 23, comprises a driven clutch spool 24 mounted upon the clutch shaft 25, provided with camming surfaces 26 and spring pressed rollers 27 co-acting therewith 5 in the usual manner to provide a one-way drive mechanism of well known type.

The clutch spool 24 has rigidly secured to it a driving gear or pinion 30 the teeth of which mesh with those of a driven gear 31 which is 10 rigidly carried by the main shaft 32 journalled in the bearing 33 of the casing 10. The said gear 31 is rigid and concentric with a locking plate or disk 34 through which the shaft 32 passes and which disk is provided with a peripheral 15 notch or recess 35 which is adapted to receive the locking toe 36 of a locking arm 37 at the close of each timing operation and thereby lock the disk 34 and gear 31 against rotation until the parts are again tripped, as will appear more 20 fully below. The said locking arm 37 is rigidly secured to a locking arm shaft 38 journalled in the bearing 39 of the housing 10, and the said locking arm is provided with a lateral and forward extension 40 to which is anchored as at 25 41 one end of a coiled tension spring 42. The other end of the said spring is anchored as at 43 to one end of bracket 44, the other end of which is pivotally secured as by pin 45 to the arm 22 of the clutch housing 23. The parts are 30 so constructed and assembled that when the locking toe 36 of the locking arm 37 drops into the notch 35 of the locking disk 34 as illustrated in Figures 1 and 2, the tension exerted by the spring 42 is completely relieved and the arm 22 and clutch housing 23 are permitted to drop to the 35 positions shown in the said figures in which positions the clutch rollers 27 have released the clutch spool 24. On the other hand when the locking toe 36 is withdrawn from the locking notch 35 so that the parts occupy the positions 40 shown in Figures 3 and 4 the spring 42 is extended and caused to exert force through the bracket 44 upon the arm 22 to move the clutch housing 23 in a counterclockwise direction, as viewed in Figure 3, causing the clutch rollers 27 to be wedged between the spool 24 and inner circumference of the housing 23, whereby motion 45 may be imparted to the spool, and through it and pinion 30 carried thereby, to gear 31 and disk 34 to drive the latter in a clockwise direction, as indicated by the arrows in Figures 1 and 3. In the meantime the driving shaft 12, which is continuously driven through any suitable source 50 of power, is rotating the driving cam or eccentric 13 to cause oscillation of the T-shaped operating lever 15 through engagement of its roller 14 with the said cam. As the cam 13 moves from its position illustrated in Figure 4 to that 55 illustrated in Figure 2, the operating lever 15 is moved in a counter-clockwise direction, as viewed in said figures, to depress its left hand arm and through the hardened steel ball 20 to impart downward movement to the clutch arm 22, returning it from the position shown in Figure 3 to that shown in Figure 1. This movement is of course against the tension of spring 42, and it has the effect of causing the clutch rollers 27 to release the spool 24, no motion being transmitted in this direction by the clutch to the pinion 30, gear 31 and locking disk 34. Continued rotation of the driving cam 13 permits the return of operating lever 15 to the position shown in Figure 4, under the influence of spring 18, and the spring 42 pulls the clutch arm 22 upwardly, thereby through the clutch rollers 27 and spool 75

24 again imparting a step or impulse to pinion 30, gear 31 and locking disk 34. It follows that so long as the locking arm 37 is in the position shown in Figures 3 and 5 with its locking toe 36 riding on the outer periphery of the locking disk 34, intermittent movement will be imparted in the manner just described through the gear 31 and disk 34 to produce step-by-step rotation of the same. This intermittent rotation is continued until the notch 35 is again brought beneath the toe 36 of operating arm 37 whereupon the said toe drops into the notch, relieving the tension of the spring 42, and permitting the clutch arm 22 to drop to the position shown in Figure 1, in which it is not affected by the continued oscillation of the operating lever 15, which is continuously moved back and forth by the driving cam 13 and spring 18 regardless of whether the batchmeter is performing a timing operation or not. 20

From what has been heretofore disclosed it will be readily understood that during each timing operation or cycle, gear 31 and locking disk 34 must perform a complete revolution, or in other words, must travel through a predetermined fixed 25 distance. In order that the length of the timing cycle may be varied at will without the necessity of changing this predetermined fixed length of travel, provision is made whereby the length of each impulse or step-by-step movement imparted 30 to the members 31 and 34 may be varied so that the rate of movement of the said members 31 and 34 throughout their fixed length of travel will be changed, and consequently the length of the timing cycle changed. The means here shown 35 for accomplishing this variation in the value of the driving impulse or step-by-step movement comprises an adjustment screw 50 threaded into a support 51 which may be rigid with the driving-shaft bearing 11. The lower end 52 of the said 40 adjustment screw is adapted to be engaged by an extension 53 of the clutch arm 22 upon its upward stroke, and obviously by moving the adjustment screw 50 up or down, as the case may be, the length of the driving stroke of the clutch 45 arm 22 may be varied and consequently the length of the intermittent movement imparted through the pinion 30, gear 31 and disk 34. A suitable scale 54 is associated with the adjustment screw 50 for indicating the amount of adjustment made, 50 and obviously the intermittent grip device exemplified by the one-way clutch 23, 24, 27, is susceptible of such infinite control through the adjustment screw 50 as to make it possible to most accurately control the total length of a 55 timing cycle.

In order to prevent back lash or reverse movement of the driven parts of the intermittent grip device and of the gear 31 during a timing operation, a suitable friction brake or other analogous 60 device may be associated with the clutch. As best shown in Figures 2, 4, and 6 of the present drawings, this braking device may comprise a pair of metal disks 55 and 56 the former of which may be mounted upon an extension of clutch 65 spool 24 while the latter is carried by a squared portion 25' of the clutch shaft 25. Between the said disks 55 and 56 is interposed a disk or annulus 57 of friction material, and the disk 56 is yieldingly pressed against said friction disk 57 70 by a spring 58, one end of which bears against the said disk 56, the other end of which bears against the shaft bearing 59 of the housing 10. Obviously any suitable form of braking device 75 may be employed in lieu of that just described

for preventing reverse movement of the driven parts to eliminate back lash.

It is customary in devices of this character to provide some sort of signal, usually an audible signal, for indicating the beginning and ending of a timing cycle and it is also desirable that a third signal or indication be given a short time, say two seconds, prior to the completion of the cycle. In order that these signals may be given in connection with the batchmeter constituting the present invention, there is provided a signalling device 60 having a pair of gongs or bells 61 and 62 which are adapted to be alternately actuated through relatively rapid movements in one direction or the other of a plunger or rod 63. The said bells however are not sounded through comparatively slow movement of said plunger 63 in either direction. The details of this signal device form no particular part of the present invention and have not been illustrated.

For moving the plunger 63 in order to sound the signals 61 and 62 at the proper time there is provided a signal actuating lever 65 which is loosely mounted upon the locking arm shaft 38. This said lever 65 is provided with a pair of lateral extensions 66 and 67 the former of which is adapted to engage with the plunger 63 to move the same while the latter extension 67 is provided with an adjustment screw 68, the lower end of which is engaged at certain times by a finger 69 rigid with and constituting an extension of the locking arm 37. The signal operating lever 65 is further provided with a toe 70 which rides upon the periphery of a spiral cam 71 which is rigidly carried by the main shaft 32 and is rotatable with the gear 31 and locking disk 34.

With the parts in the positions shown in Figure 1, at the start of the timing operation the locking arm shaft 38 is moved rather suddenly in a counter-clockwise direction to withdraw the locking toe 36 from the locking notch 35 to start the mechanism in operation. This movement depresses the extension 69 of the locking arm 37 and permits the signal operating lever 65 and plunger 63 to fall under the influence of gravity, thus sounding one of the gongs, say 62. This brings the toe 70 of the arm 65 into engagement with the low portion of the spiral cam 71, and as this cam is rotated along with the gear 31 and disk 34 to bring its high portion beneath the toe 70, the arm 65 and plunger 63 are gradually raised to the positions shown in Fig. 5 which movement is so slow as not to cause sounding of the gongs. At a predetermined time before the locking toe 36 drops into the locking notch 35, say two seconds, the toe 70 of signal operating lever 65 reaches the abrupt shoulder 72 between the high and low portions of the cam 71 and drops to the low portion thereby permitting the plunger 63 to fall rapidly under the influence of gravity and again sound the signal, such as 62. At the completion of the timing cycle the toe 36 of operating arm 37 drops into notch 35 thereby rapidly elevating the finger 69, which through contact with the adjustment screw 68 rapidly raises the signal lever 65 and plunger 63 sounding of the signal gong 61. The signals 61 and 62 may be of different tones and it thus results that suitable signals are given at the beginning and close of the timing cycle and a warning signal is given at a predetermined time preceding the close of the cycle.

With the parts in the position shown in Figure 1 in order to start a timing cycle it is only necessary that the locking arm shaft 38 be moved in

a counter-clockwise direction a sufficient distance to withdraw the locking toe 36, of arm 37 from the notch 35 in disk 34, whereupon the intermittent drive above described will proceed to move the gear 31 and disk 34 in a clockwise direction by a series of step-by-step movements. The means for moving the shaft 38 to start the batchmeter into operation may vary according to the particular machine, the operations of which are to be timed, but since the present mechanism has been designed primarily for use in connection with a concrete mixer, such apparatus has been indicated in Figure 7 and one form of power drive and of tripping means for the batchmeter has been shown therein. In the said figure the mixing drum is indicated at 80, being suitably mounted for rotation in the frame-work 81. The batchmeter casing 10 is indicated in broken lines in its position at the side of the mixing drum 80 and its driving shaft 12 is shown as being connected through universal joints 82 and drive shaft 83 with a sprocket or gear 84 journalled within a housing 85 carried by a portion of the framework 81. The sprocket or gear 84 may be continuously rotated through any suitable driving mechanism from the power plant of the mixer.

The locking arm shaft 38 of the batchmeter is provided with an arm or lever 86 rigidly secured to the shaft to turn therewith, which lever terminates in a toe 87 which is adapted to be moved to the broken line position illustrated in Figure 7 when the batchmeter is in operation, where it engages with a hook 88 carried by a link 89 which is connected to the foot lever 90, which controls through the extension 91 and link 92, the power discharge mechanism, the automatic control mechanism, and/or other similar instrumentalities of the mixer. It thus results that with the parts in this position the operation of the power discharge, or the automatic control mechanism, is prevented so long as the batchmeter is in operation, since obviously the foot lever 90 cannot be depressed when the toe 87 of lever 86 is beneath the hook 88.

The locking arm shaft 38 of the batchmeter also carries a starting lever 93 which is loosely mounted on the said shaft and which is provided with a laterally extending ear 94 carrying an adjustment screw 95, which screw is adapted to engage with the lever 86 as clearly shown in Figures 6 and 7. The lower end of the starting lever 93 is connected by a link 96 to an arm 97 rigid with a jack shaft 98 supported by the frame-work 81, which shaft also carries an arm 99 having a laterally extending link 100 which terminates in a toe 101 disposed in the path of a lug 102 carried by the arm 103, which supports the charging skip of the mixer, not shown. The lug 102 is so positioned that as the charging skip arm 103 approaches its highest elevation as indicated in broken lines in Figure 7, the said lug engages with the projection 101 of the link 100 and moves said link toward the right, as viewed in Figure 7, thereby moving the arms 99 and 97 to their broken line positions. This motion is transmitted through link 96 to starting lever 93 and through its adjustment screw 95 to the lever 86 and thence to the locking arm shaft 38 of the batchmeter to withdraw the locking toe 36 of locking arm 37 from notch 35. The arm 86 may have a tension spring 104 for returning it and the shaft 38 to inoperative or stopped position.

The front of the housing 10 is normally closed by a cover plate 105 retained in position by suit-

able screws 106. The said cover plate is provided with an opening 107 through which access may be had to the adjusting screw 50 for the purpose of varying the length of the timing cycle. This opening is normally closed by the disk 108, Figure 4, carried on a stud 109 rigid with the locking bar 110. A spring 111 yieldably forces the closure 108 into engagement with the surface of the cover plate 105. The locking bar 110 is pivoted as at 112 in the ears 113 carried by cover member 105, and its upper end 114 is bifurcated to straddle an eye 115 through which may be passed the shackle of a suitable lock, indicated in dotted lines at 116. The opening 107 may thus be sealed against access to the adjustment screw 50, whereby unauthorized changing of the timing cycle may be prevented.

It is customary in devices of this kind to provide a counting and registering mechanism whereby the number of batches mixed may be registered and such device is indicated in the present instance at 120. It may be actuated from the locking arm 37, but since such devices are common in the art, the details of the present register and actuating mechanism have not been shown.

The cover plate 105 may be provided with a sight opening closed by a glass or other transparent member 117 through which the register 120 may be viewed from the outside.

It is preferred to partially fill the housing 10 with a suitable lubricant in order that the clutch and other associated parts may be properly lubricated and for this purpose a filling opening 121 may be provided in the said housing and normally closed by a plug 122. The casing may be filled with the lubricant up to the level of its opening, which will be sufficient to supply all necessary lubrication to the clutch and other associated parts.

It is obvious that those skilled in the art may vary the details of construction as well as the precise arrangement of parts without departing from the spirit of the invention, and therefore it is not wished to be limited to the above disclosure except as may be required by the claims.

What I claim is:

1. In a batchmeter for timing an operation, a driven member, means for driving said member, including a constantly moving instrumentality and a yielding member; and means controlled by said driven member for rendering said yielding member inoperative irrespective of continued movement of said instrumentality, to stop the drive at the end of a timing operation.

2. In a batchmeter for timing an operation, a driven member; means for driving said member; a spring for moving said driving means; and means controlled by said driven member for relieving the force exerted by said spring upon said driving means, at the end of a timing operation, to stop the drive.

3. In a batchmeter for timing an operation, a driven member; means arranged to intermittently drive said member in one direction, including a member movable to and fro, a spring for moving said member in the driving direction, and constantly operating power means for moving said member in the other direction; and means operable by said driven member at the end of a timing operation for rendering said spring inoperative to stop the drive irrespective of continued movement of said power means.

4. In a batchmeter, for timing an operation, a driven member; means including an intermit-

tent grip device for driving said member in a predetermined direction; resilient means for moving said intermittent grip device in the driving direction; a constantly oscillated arm for moving said device in the other direction; and means for rendering said resilient means inoperative at the conclusion of a timing operation, to stop the drive irrespective of continued operation of said arm. 5

5. In a batchmeter for timing an operation, a driven member; means including a minutely variable stroke intermittent grip device for driving said member in one direction; resilient means for moving said intermittent grip device in the driving direction; constantly operating power means for moving said grip device in the opposite direction against the action of said resilient means; and means controlled by said driven member for rendering said resilient means inoperative at the conclusion of a timing operation, 20 and stop the drive irrespective of continued operation of said power means.

6. In batchmeter mechanism for timing an operation, a driven member movable a uniform fixed distance during each timing operation; means including an intermittent grip device for driving said member always in the same direction; and means for minutely varying the length of each movement imparted by said driving means to control the total time required for said driven member to travel said fixed distance. 25

7. In batchmeter mechanism for timing an operation, a driven member; means including a spring for driving said member; and means for relieving the force exerted by said spring on said driving means at the end of a timing operation 35 to stop the drive, a portion of said relieving means engaging a portion of said driven member to lock the latter when the drive is stopped.

8. In batchmeter mechanism for timing an operation, a driven member; means including an intermittent grip device for driving said member; means for locking said driven member against movement; and resilient means between said locking means and said intermittent grip device, said locking means when moved to unlocking position causing said resilient means to exert force on said intermittent grip device to cause the latter to move said driven member. 40

9. In batchmeter mechanism for timing an operation, a driven member, means including a clutch for driving said member; an arm engageable with a portion of said driven member for locking it against movement; and a spring between said arm and clutch, said locking arm when 55 in locking position relieving the force exerted by said spring, and when moved to unlocking position causing said spring to exert force on said clutch and cause it to drive said driven member.

10. In batchmeter mechanism for timing an operation, a driven member; means including a one-way clutch for driving said member; a movable arm engageable with a portion of said driven member for locking it against movement; a spring connected to said arm and said clutch, 65 said arm when in locking position relieving the force exerted by said spring, and when moved to unlocking position causing said spring to exert force to move said clutch in one direction; and means for moving said clutch in the opposite 70 direction against the action of said spring.

11. In batchmeter mechanism for timing an operation, a driven member; means including a one-way clutch for driving said member; a movable arm engageable with a portion of said mem- 75

ber for locking it against movement; a spring connected to said arm and said clutch, said arm when in locking position relieving the force exerted by said spring, and when moved to unlocking position causing said spring to exert force to move said clutch in its driving direction; and means for moving said clutch in its free direction against the action of said spring.

5 12. In batchmeter mechanism for timing an operation, a driven member having a recess; means including an intermittent grip device for driving said member in a single direction; an arm having a portion receivable in said recess for locking said member against movement; a spring connected to said arm and said intermittent grip device, said arm when in locking position relieving the force exerted by said spring, and when moved to unlocking position causing said spring to exert force on said intermittent grip device in its driving direction; and power driven means for moving said intermittent grip device in its free direction against the action of said spring.

10 13. In batchmeter mechanism for timing an operation, provided with a signal, a timing member, and means for locking said member against movement and releasing it, the combination of means operable by said locking means for actuating said signal as said locking means is moved to and from locking position.

15 14. In batchmeter mechanism for timing an

operation, provided with a signal, a timing member, and means for locking said member against movement and releasing it, the combination of means operable by said locking means for actuating said signal as said locking means is moved both to and from locking position; and additional means operable by said timing member for independently actuating said signal intermediate its actuation by said locking means.

15 15. In batchmeter mechanism for timing an operation, provided with a signal and a timing member, the combination of an arm movable into and out of engagement with said timing member to lock and release the same, said arm having a portion for causing actuation of said signal upon movement of the arm both to and from locking position.

10 16. In batchmeter mechanism for timing an operation, provided with a signal, a timing member, and an arm movable into and out of engagement with said timing member to lock and release the same, the combination of means intermediate said arm and signal for actuating the latter as said arm is moved both to and from locking position; and cam means for moving said actuating means independently of said arm, to cause it to actuate said signal intermediate its actuation by said arm.

RUDOLPH F. LINDOW. 30
